UNITED STATES PATENT OFFICE.

SALVATORE J. BUZZINI, OF NEW YORK, N. Y.

FIRE-ARM.

SPECIFICATION forming part of Letters Patent No. 340,482, dated April 20, 1886.

Application filed January 15, 1886. Serial No. 185,699. (No model.)

To all whom it may concern:

Be it known that I, SALVATORE J. BUZZINI, of the city, county, and State of New York, have invented a new and useful Improvement 5 in Fire-Arms, of which the following is a full, clear, and exact description.

This invention relates to breech-loading and other fire-arms, including rifles; and it consists in novel means, substantially as herein-10 after described, and pointed out in the claims, for securing the barrel of the fire-arm to its place, and for providing for its ready attachment and detachment or replacement by another barrel, when required, without having 15 recourse to a gunsmith or other skilled artisan, which will be found a great convenience to sportsmen and others engaged in military or target practice. It also provides for a more accurate return of the barrel to its normal po-20 sition than is practicable when the barrel is secured to its place by screwing it into the stock of the fire-arm, and it furthermore pro-25 vides for the ready dismemberment and securing of the fore-arm and stock as well as the barrel of the gun.

Reference is to be had to the accompanying drawings, forming a part of this specification, in which similar letters of reference indicate corresponding parts in all the figures.

30 Figure 1 represents a longitudinal section, upon the line *x x* in Fig. 2, of a fire-arm in part with my invention applied. Fig. 2 is a plan view of the same. Fig. 3 is a plan, upon a larger scale, of a portion of the stock and fore-arm with certain securing means applied, the barrel being removed. Fig. 4 is a trans-35 verse section upon the line *y y* in Fig. 1, and Fig. 5 a transverse section upon the line *z z* in Fig. 1.

40 A is the stock, B the fore arm, and C the barrel, of a breech-loading fire-arm.

The fore-arm B is represented as being constructed to fit against the forward end of the stock A and to engage therewith, as by a 45 dowel-pin, *b*, and rear-projecting lapping pieces *c*, arranged to enter within the forward half-socket portion, *d*, of the stock. It is se-50 cured to its place when thus fitted to the stock by means substantially as hereinafter described.

The barrel C is held down to its place with-5 in the fore-arm B by one or more clamping rings or bands, D, slid to their places over the barrel and over the forward, tapering end of the fore-arm, and each secured, when slid or driven home, by a spring-hook catch, E, at-55 tached to the fore-arm and engaging with or in a hole, *e*, in the band. Only one of these catches is here shown, and it is represented as arranged upon the under side of the fore-arm, 60 within a recess therein; but it might be ar- ranged upon the side of the fore-arm or upon opposite sides thereof, when desired to make room for a ramrod, or as other circumstances may direct.

65 The back-end portion of the barrel C, which is provided with flanges or projections *f f*, lies within the half-socket portion *d* of the stock, and may or may not be provided with a rear smooth extension, *g*, arranged to fit 70 within a receiving smooth socket or tubular or chambered portion, *h*, of the stock. This smooth socket-like fit of the barrel in the stock, however, is preferred, and importantly differs from a screw-threaded fit of the barrel with 75 the stock. When the barrel C is fitted to its place, it is firmly held down thereto at its rear end and secured from forward or longitudinal movement by a locking-cap, G, which is con-80 structed to clip or hug the upper half of the portion of the barrel within the flanges *f f*, and either to enter at its sides down within the half-socket portion *d* of the stock, as shown in Fig. 5, or to pass down the outside thereof, as desired. Said detachable saddle-like cap 85 G, when thus fitted to its place, may be removably held or secured in various ways—as, for instance, by a key or screw passing through it and the stock; but it is preferred to secure it by a button, H, pivoted at *i* to the interior of the bottom of the half-socket *d*, and engag-90 ing at its ends with the sides of the cap through slots *k* therein, and with or through slots or notches *l* in the sides of the half-socket portion *d* of the stock. This button H is turned to 95 make the engagement, as described, or to dis-engage it, as required, by means of a rod or bar, I, pivoted to it, and arranged to extend into the fore-arm beneath the barrel, and pro-100 vided at or near its forward end with a hook-

ing pin or lip, *m*, thus making the bar *I* a hook—one that when the button *H* is turned by it to lock the cap *G* engages with an aperture, *n*, in the bottom of the fore-arm, and serves not only to hold the button *H* in its engaged position, but also to hold the fore-arm *B* up against the front end of the stock *A*. The cap *G* is constructed on its top to also form the base-piece *J* of the hinged and adjustable sight piece *J J'*—such, for instance, as is ordinarily arranged upon the barrel of the fire-arm, whereby said cap, in addition to its regular function of holding the barrel, also forms the sight-carrier.

15 When it is required to detach the barrel *C*, all that is necessary is, first, to press in the hook-catch *E*, so as to disengage it from the clamping-band *D*, which is then slipped or slid from the barrel and fore-arm *B* of the gun, after which the fore-arm is slightly tipped down in front to disengage it from the hook-bar *I*, and is drawn out of and disengaged from the stock *A*. The exposed hook-bar *I* is then worked by the fingers to disengage the button *H* from its lock or hold on the cap *G*, to permit of the removal of the cap, after which the barrel *C* may be removed from the stock. When it is required to return the barrel to its place, or to 30 replace it by another interchangeable one, either of the same or different bore, the barrel is placed, as required, in the half-socket *d* of the stock, the cap *G* applied over the barrel between the flanges *ff*, and the hook-bar *I* adjusted to engage with the cap and stock. The fore-arm is then adjusted to its place, and the band *D* secured in its position, causing the hook-bar *I*, which engages with the fore-arm, to be secured in its locking position.

35 40 Having thus fully described my invention, I claim as new and desire to secure by Letters Patent—

1. The combination, with the stock *A* of the gun and the detachable barrel *C*, of the independent and separately-detachable barrel-

holding cap *G*, made to engage with the barrel and stock in advance of the rear end of the barrel, and of strap or saddle-like construction, with its closed end shaped to clip the upper portion of the barrel, but left wholly free or open beneath the barrel, whereby said cap may be fitted down over the barrel after the latter has been inserted to its place, and the barrel cannot be detached till after the cap has been disengaged, substantially as specified. 50 55

2. The combination, with the stock *A*, having a partial socket portion, *d*, and the barrel *C*, fitting down within said socketed portion, of the detachable saddle-like independent barrel-holding cap *G*, of closed construction at its upper end, but left wholly open beneath, and adapted to engage with the stock and barrel, and means for securing said cap when so engaged, essentially as described.

3. The combination, with the half-socketted portion *d* of the stock, the detachable barrel *C*, and detachable fore-arm *B*, of the barrel-holding detachable saddle-like cap *G* and the button *H* with its attached hook-bar *I*, adapted to lock or hold said cap and fore-arm to their places, substantially as specified. 65 70

4. The combination, with the stock of the fire-arm and its detachable fore-arm *B*, constructed to engage with the stock, of the automatic-locking hook-bar or catch *I*, connected and engaging at its opposite ends, respectively, with the stock and fore-arm, essentially as and for the purpose herein set forth. 75

5. The clamping ring or band *D*, arranged to embrace both the barrel and fore-arm of the gun, and the hook-bar *I*, connected with the stock of the gun and arranged to engage with the fore-arm thereof, in combination with the detachable saddle-like cap *G*, the detachable barrel *C*, and the detachable fore-arm *B*, substantially as specified. 80 85

SALVATORE J. BUZZINI.
